UNITED STATES PATENT OFFICE.

RAYMOND PERCIVAL PAYNE, OF LEEDS, ENGLAND, ASSIGNOR TO GEORGE MANN & COMPANY, LIMITED, OF LEEDS, ENGLAND.

ROTARY LITHOGRAPHIC MACHINE.

1,113,137.

Specification of Letters Patent.

Patented Oct. 6, 1914.

Application filed November 21, 1912. Serial No. 732,733.

To all whom it may concern:

Be it known that I, RAYMOND PERCIVAL PAYNE, a subject of the King of Great Britain, residing in Leeds, England, and whose post-office address is 156 Beeston road, Leeds, in the county of York, England, engineer, have invented certain new and useful Improvements in Rotary Lithographic Machines, of which the following is a specification.

In rotary lithographic machines as heretofore constructed, there has been difficulty in obtaining the requisite depth of color in the printed sheet unless the portion of the 15 periphery surface of the cylinder which carries the design-plate or the like, is not more than half the full periphery surface. This difficulty is due to the fact that the water which lies upon the surface of the design- 20 plate or the like (an essential condition of lithographic printing) is more or less absorbed by the ink upon the inking rollers and in this manner the printing quality of the ink is impaired, unless these inking 25 rollers are separated from their contact with the water for a period of at least as long as the period of the contact.

By this invention in any rotary lithographic machine in which the design-plate or the like occupies more than one-half of the periphery surface of the design cylinder, or the whole of that surface, the inking rollers are distributed into two or more groups of one or more rollers, and it is arranged that the rollers or roller of one at least of these groups are not in contact with the water which lies upon the surface of the design-plate at each revolution or portion of a revolution of the design-cylinder. 30

40 In other words, if a first group of rollers ink the design plate during one revolution (the plate in this case occupying the whole periphery of the design-cylinder) this group is taken out of action at the end of 45 this revolution and a second group of rollers is brought into action so as to ink the plate during the next revolution. If the plate does not occupy the whole periphery of the design-cylinder the rollers are of 50 course in operation only during a portion of the revolution. For instance, at least one of the groups of one or more rollers may be lifted at each revolution or part of a revolution so as to effect the object in view.

55 In the accompanying diagrammatic draw-

ing, the plate cylinder *a* of a rotary lithographic machine, is fitted with a plate *b* which is shown occupying the whole periphery of the cylinder. Inking rollers *c*¹ and *c*² are shown arranged in two groups of four 60 rollers in each group, rollers *c*¹ being in contact with the plate and rollers *c*² out of contact with the plate. A means for carrying the ink from an ink fountain *w* to the inking rollers *c*¹ and *c*² is also shown, and 65 damping rollers *d* are shown in contact with the plate. Shaft *e* is carried in bearings in the frame-work of the machine and is arranged to make two revolutions to each revolution of the cylinder *a*.

70 On the shaft *e* are two cams, not shown in the drawing, one of which engages the runner *f* and thus moves an arm *g* on a shaft *h* which also carries an arm *k*. The latter is connected by link *l* with a lever *m*, 75 which is pivoted on a portion of the bearing of the cylinder *a*. Pins *n* *n* in the lever *m* form pivots for links *p* *p* which are provided at their other ends with pins *q* *q* forming pivots for levers *r* *r*. The levers *r* *r* 80 carry forked bearings *s* *s* for the inking rollers *c*¹, *c*¹ and are also pivoted on pins *t*, *t*. The links *p* *p* are also provided with cam shapes embracing the pins *u* *u* so as to actuate also levers *v* *v* and the remainder of 85 the rollers *c*² of this group. The whole of this motion is shown in the position in which the rollers *c*¹ are in contact with the plate. The parts *f*¹, *v*¹, are similar to the parts *f*, *v*, and operate similarly on the inking rollers *c*², and the whole of this motion is shown in the position in which the rollers *c*² are raised from the plate. By 90 such means each group of rollers is raised and lowered alternately during each revolution of the plate cylinder, the cam shapes on the shaft *e* being so arranged that there is always one group of rollers in contact with the plate *b*.

Having now described the nature of my 100 said invention and the best means I know of carrying the same into practical effect, I claim:

1. In a rotary lithographic machine, the combination of a design cylinder adapted 105 for printing a design extending over more than half its periphery, a plurality of groups of inking rollers, and means adapted to operate each group in turn for inking the design cylinder during a complete 110

revolution thereof throughout the process of printing.

2. In a rotary lithographic machine, the combination, with a design cylinder and its design plate, of a plurality of groups of inking rollers adapted to be used alternately during the progress of printing, and means operating to move the said groups of inking rollers continuously and alternately one group at a time into and out of contact with the design plate during the progress of printing.

3. In a rotary lithographic machine, the combination with a design cylinder and its design plate, of a plurality of groups of

inking rollers adapted to be used alternately during the progress of printing, and means operating to move the said groups of inking rollers continuously and alternately a number at a time less than the whole of such groups, into and out of contact with the design plate during the progress of printing. 20

In testimony whereof I have signed my name to this specification in the presence of 25 two subscribing witnesses.

RAYMOND PERCIVAL PAYNE. [L. S.]
